**PORTABLE RADIO RECEIVER FOR BROADCAST
RECEPTION**

Edward Klein, Chicago, Ill., assignor to Motorola, Inc.,
Chicago, Ill., a corporation of Illinois

Application June 15, 1955, Serial No. 36,516

Term of patent 7 years

(Cl. D56—4)

Fig. 1.

Fig. 1 is a front perspective view of a portable radio receiver for broadcast reception showing my new design. The dominant features of the design are in full lines and show the handle therefore in turned position;

Fig. 2 is a side elevational view thereof;

Fig. 3 is a rear elevational view thereof; and
Fig. 4 is a top plan view thereof.

I claim:

The ornamental design for a portable radio receiver for broadcast reception, as shown and described.
